UNITED STATES PATENT OFFICE.

WILLIAM EWAN MACKENZIE, OF LONDON, ENGLAND.

TRANSPORTER.

Application filed June 2, 1926, Serial No. 113,205, and in Great Britain November 16, 1925.

This invention of improvements in transporters has relation to transporters of the kind in which carriers are mounted on an overhead runway on which they always move in the same direction, the carriers being loaded at one point and discharged at another point from which they return to the loading point along a return path.

The invention has for object to provide improvements in such transporters by means of which certain advantages shall be obtained, and particularly to provide a transporter in which the carriers are maintained in continuous movement.

The invention also has for object to provide improvements in transporters as referred to in the preceding paragraphs by which the rate of movement of the carriers is increased between the points at which loading and unloading are effected.

The invention also has for object to provide improvements in transporters as referred to in the preceding paragraphs by which the loads are suspended from the carriers through hoisting and lowering gear and the hoisting and lowering gear is operated automatically when leaving and approaching the loading and unloading points.

The invention further has for object to provide improvements in transporters as referred to in the preceding paragraphs by which the hoisting and lowering gear of a carrier is connected with and operated by a preceding or a following carrier or by a preceding and following carrier.

The invention further has for object to provide improvements in transporters as referred to in the preceding paragraphs by which the hoisting and lowering gear is operated by the difference in the rate of movement of the carrier from which the load is suspended and a preceding or following carrier or a preceding and following carrier.

In order that the invention, the objects of which have been set forth, may be clearly and readily understood, reference will now be made to the embodiment illustrated on the accompanying drawings, on which:—

Fig. 1 is a side view;
Fig. 2 an end view; and
Fig. 3 a plan view of a transporter, the runway being mounted on standards or gantries in relation to which it is adjustable in a vertical plane and the standards or gan-

tries being mounted on wheels running on rails so that the transporter is adjustable as to position.

Fig. 4 is a plan view of one end of a runway;

Fig. 5 a diagrammatic view of an end member of the runway with the transerrer shown in three positions;

Fig. 6 is a sectional view on the line IV—IV of Fig. 4; and

Fig. 7 is a cross section on the line VI—VI of Fig. 6.

Fig. 8 is a side elevation;

Fig. 9 an end elevation; and

Fig. 10 a plan view of a carrier.

Fig. 11 is a detail view of the bolster of a carrier showing the carriage mounted thereon.

Figs. 12 to 15 inclusive are diagrammatic representations of a portion of a runway with carriers mounted thereon and provided with several arrangements of hoisting gear.

Referring to Figs. 1 to 3 inclusive.

11, 11 are standards or gantries mounted on wheeled platforms or trucks 12 and running on rails 13. The standards or gantries 11, 11 carry the runway which consists of an endless path constituted of a pair of trussed or other girders or beams 14 placed parallel to one another and united at their ends by curved or semicircular members 15, also of trussed or girder like construction. The girders or beams 14 and the end members 15 are connected and braced so as to constitute a unitary structure. The runway 14, 15 is mounted in the standards or gantries 11, 11 so as to be adjustable in relation thereto in a vertical plane and as the standards or gantries 11 are movable along the rails 13 the runway 14, 15 is movable also in a horizontal plane. The position or height or positions and heights of the point or points at which loading or unloading or loading and unloading can be effected is or are varied by adjustment of the runway 14, 15 in a horizontal plane or in a vertical plane or in both horizontal and vertical planes. The mounting in the standards or gantries of the runway 14, 15 and the means for effecting its vertical adjustment in relation thereto are not illustrated, as they form no part of the present invention.

Referring now to Figs. 4 to 7 inclusive.

The runway 14, 15 is provided with rails 16 on which the carriers hereafter described

with reference to Figs. 8 to 11 inclusive, run. The rails 16 form integers in the construction of the runway and are at the lower part thereof. The runway 14, 15 is of such design and construction that the carriers run on the rails 16 within the girders or beams and there is free and unobstructed passage for the ropes, chains or the like by which the loads are suspended from the carriers and are raised and lowered.

17, 17 are worms or screws. Each is mounted within, and extends the full length of, a member 14 of the runway. Each worm or screw 17 is in one length or in a plurality of lengths and when in several lengths, the units are joined together by flexible couplings of any suitable and convenient construction. The threads of the worms or screws 17 are of rectangular or other section and are wound around and secured to stocks or cores, which are preferably tubular. The worms or screws 17 are mounted in bearings (not shown) disposed so that the worms or screws 17 are above the rails 16 and each worm or screw occupies a position that is nearer the inner of the rails 16. The worms or screws 17 are driven by an electric motor 18 mounted on members attached to the girders or beams 14. The shaft 19 of the motor 18 is geared by spur gearing 20 to a shaft 21 which, in turn, is geared by spur gearing 22 to a shaft 23. The shaft 23 is geared to the worms or screws 17 by spur gearing 24 such that the two worms or screws 17 rotate in opposite directions. The pitch of the worms or screws 17 is not uniform throughout the whole of their lengths, but is varied at one or more places. The worms or screws 17 are employed to drive the carriers hereafter described and the arrangement is such that when the carriers are in engagement with the parts of the thread that are of varying pitch they are propelled at an increasing or decreasing rate compared with that at which they are driven when in engagement with parts of the thread of uniform pitch.

Referring now to Figs. 8 to 11 inclusive.

A carrier comprises a bolster 27 carried by two bogies 25, 26 mounted on flangeless wheels 28 maintained on the rails 16 by three wheels 29, 29, 30 turning on vertical axes. The axes of the wheels 29, 29, 30 are carried by the bogies 25, 26 and the wheels are so arranged that the wheels 29 bear on the inner side of the outer rail of the rails 16 and the wheel 30 on the outer side of the same rail. The bolster 27 consists of a frame (Fig. 11) having at each end an extension 31 by which the pivotal connection of the bogies 25, 26 with the bolster 27 is effected, and on its upper face and at one side or edge thereof two upwardly extending and parallel members 32. These members 32 are connected together by rods 33 on which a car-

riage 34 is mounted and movable. Interposed between the carriage 34 and members 32 and disposed between the rods 33 are springs 35 which act to maintain the carriage 34 centrally between the members 32 and to act as buffering springs to take up or absorb any shocks to which it may be subject. Mounted on one side of the carriage 34 are two rollers 36, 37 which are disposed in the same vertical plane but are not in the same horizontal plane. The rollers 36, 37 are further such that one engages or bears against the under side of the thread of the worm or screw 17 and the other against the opposite side. 38 is a third roller mounted on the carriage 34: it is mounted on the under side of the carriage 34 and turns about a vertical axis.

39 are pulleys mounted on a horizontal axis on the lower part of the bolster 27. These pulleys 39 form part of a block and tackle of which 40 is the third pulley, 41 the hook and 42 the rope. In the arrangement now being described the rope 42 passes over the pulleys 39 and is led forward and aft, the one end of the rope being anchored to the bolster of the preceding carrier and the other end to the bolster of the following carrier as more clearly shown in Fig. 12. 43 are guide pulleys mounted on the bolster 27 and 44 are anchors on the bolster for the ropes of blocks and tackle on the preceding and following carriers.

Referring now to Figs. 12 to 15 inclusive.

Fig. 12 shows a worm or screw 17 of varying pitch at the central portion of its length and of uniform pitch for the remainder of its length. Meshing with the worm or screw 17 are five carriers. It will be understood that when the worm or screw is driven, the carriers are set in motion and that as each carrier approaches and leaves the central portion of the worm or screw its rate of progression is first decreased and then increased. In other words, the carriers tend to crowd together at the central portion of the worm or screw and then to separate. As one carrier approaches another the hoisting and lowering gear is operated and the hook 41 is lowered to permit a load to be attached or detached. As the carriers move apart, the hoisting and lowering gear is operated and the hook 41 is raised.

In Figs. 13, 14 and 15 other arrangements of block and tackle to that shown in Fig. 12 are illustrated.

The description so far has described the arrangement of parts so far as they relate to the members 14 of the runway and the movement of the carriers on such parts of the runway. To enable the carriers to be transferred from one part 14 of the runway to the other part 14 thereof, the two parts 14 are united at their ends by the curved or semi-circular members 15 and the means

by which the carriers are propelled along these members 15 will now be described with reference to Figs. 4 and 5.

43^a is an arm mounted at the one end of 5 a spindle 44^a which is rotatably mounted between the members 14. The spindle 44^a at its upper end carries a worm wheel 45 which meshes with a worm 46 on the shaft 23. The arm 43^a is consequently driven 10 from and by the motor 18. The arm 43^a is slotted longitudinally from each end. Z (Fig. 5) is the centre of the member 15. The spindle 44^a is mounted and arranged so that it is not coaxial with the centre Z. 15 When a carrier approaches the end of the worm or screw 17 its roller 38 enters the longitudinal slot in the arm 43^a, which is then at position Y, and the carrier is propelled around the curve first at a gradually 20 decreasing rate of progression and then at a gradually increasing rate. This variation in the rate of progression is due to the alteration in the position at which the roller 38 contacts with the arm 43^a. The arrangement therefore permits the hoisting and 25 lowering gear to be worked at the ends of the transporter.

What I claim is:—

1. A transporter comprising an endless 30 runway, a plurality of carriers mounted thereon, means for driving the carriers along the runway so that they are maintained in continuous movement and are caused to travel faster between the points 35 at which they are loaded and unloaded and hoisting gear carried by each carrier operatively connected with and adapted to be actuated by another carrier through difference in the rates of progression of the 40 carriers.

2. A transporter comprising an endless runway, a plurality of carriers mounted thereon, a worm mounted on the runway meshing with the carriers to drive them 45 along the runway continuously and hoisting gear carried by each carrier operatively connected with and adapted to be actuated by another carrier.

3. A transporter comprising an endless 50 runway, a plurality of carriers mounted thereon, a worm mounted on the runway meshing with the carriers to drive them along the runway continuously and having portions of variable pitch so that the carriers have different rates of progression and 55 hoisting gear carried by each carrier, the hoisting gear of each carrier operatively connected with and adapted to be actuated by another carrier through differences in the rates of progression of the carriers.

4. A transporter comprising an endless runway, a plurality of carriers mounted thereon, means for driving the carriers 60 along the runway so that they are maintained in continuous movement and are

caused to travel faster between the points at which they are loaded and unloaded, and hoisting gear carried by each carrier connected with a preceding and following carrier and adapted to be actuated by differences in the rates of progression. 70

5. A transporter comprising a runway consisting of two straight portions united at their ends by curved portions, a plurality of carriers mounted thereon, means for driving the carriers along the runway so that they are maintained in continuous movement and are caused to travel faster between the points at which they are loaded and unloaded and hoisting gear carried by each 80 carrier operatively connected with and adapted to be actuated by another carrier through differences in the rates of progression of the carriers.

6. A transporter comprising a runway 85 consisting of two straight portions united at their ends by curved portions, a plurality of carriers mounted thereon, worms mounted in the straight portions of the runway and meshing with and driving the carriers, 90 and means to propel the carriers round the curved portions of the runway at varying rates of progression.

7. A transporter comprising a runway 95 consisting of two straight portions united at their ends by curved portions, a plurality of carriers mounted thereon, worms having portions of variable pitch meshing with and driving the carriers along the straight portions of the runway at different rates of progression, an arm mounted to rotate in a horizontal plane at each of the curved portions of the runway, means on the arms and carriers to interengage so that the carriers are driven around the curved portions by the 100 arms, and hoisting gear carried by each carrier operatively connected with and actuated by another carrier through differences in the rates of progression of the carriers. 105

8. A transporter comprising a runway 110 consisting of two straight portions united at their ends by curved portions, a plurality of carriers mounted thereon, worms meshing with and driving the carriers along the straight portions of the runway, an arm mounted to rotate in a horizontal plane at each of the curved portions of the runway 115 and mounted out of centre, and interengaging means on the arms and carriers.

9. A transporter comprising an endless 120 runway consisting of two straight portions united at their ends by curved portions, a plurality of carriers mounted thereon, means for driving the carriers along the straight portions of the runway, and means to propel the carriers around the curved portions of the runway at varying rates of progression. 125

10. A transporter comprising an endless runway consisting of two straight portions 130

united at their ends by curved portions, a plurality of carriers mounted on the runway, means for driving the carriers along the straight portions of the runway in continuous movement and for causing the carriers to travel faster between the points at which they are loaded and unloaded, hoisting gear carried by each carrier and actuated by another carrier through differences in the rates of progression of the carriers, and means for propelling the carriers around the curved portions of the runway at varying rates of progression, whereby the hoisting gear of the carriers are actuated at such curved portions of the runway.

11. A transporter comprising a runway, a plurality of carriers thereon, means for driving said carriers along the runway and for decreasing the rate of progression of the carriers as they pass points of loading and unloading, and hoisting gear carried by each carrier and operatively coupled with another carrier for actuation as each carrier passes a point of loading and unloading and its rate of progression is decreased, by the carrier with which coupled traveling at a greater rate of progression.

12. A transporter comprising a runway consisting of straight portions united at

their ends by a curved portion, a plurality of carriers mounted thereon, means for driving the carriers along the straight portions, an arm mounted to rotate in a horizontal plane at the curved portion of the runway, said arm longitudinally slotted and mounted for rotation on an axis off center with respect to the axis of the curve, and means on the carriers for engagement in said slotted arm whereby each carrier is propelled around the curved portion of the runway at varying rates of progression.

13. In a transporter including a runway having a curved portion, a carrier on said runway, and means for propelling said carrier around the curved portion of the runway, comprising an arm mounted for rotation in a plane substantially parallel to the plane of the curved portion of the runway around an axis off center with respect to the center of curvature of the curved portion, and means on the carrier for engagement by said arm whereby the carrier is propelled around the curved portion of the runway at different rates of progression.

Dated this twenty second day of May, 1926.

WILLIAM EWAN MACKENZIE.
